William H. Davis
Design for Fork or Spoon Handle.
Patented Nov. 1, 1859.

No. 1,166.

Design For Handle
By William H. Davis of Westbury Conn
1859
Edward H. Davis
Drawing of Fig. 1

Wes. 1166

William H. Lewis, of Glastenbury, Conn.
Letters Patent No. 1166. Dated Nov. 1. 1859.

The schedule referred to in these Letters Patent and making part of the same,

To all whom it may concern:

Know, that I, William H. Lewis, of Glastenbury, County of Hartford and State of Connecticut, have invented or produced a new and original design, or configuration, to be Worked, Stamped, or Cast upon a handle and I do hereby declare that the following is a full and exact description of the same,

2

Wes. 11 60

In the accompanying drawings-

Fig: 1, & 2. represent a handle, which I propose to use for various purposes, and, of various kinds of metals, in the center or nearly so, and at the broadest part of the handle, A. is a configuration of a Shield, B. is a configuration of an Urn or Vase, growing out of which and surrounding the shield A. is a configuration of a Strawberry fruit, Vine and foliage.

A configuration of the vine extends from the end C, around the edge of the handle, terminating in a small cluster of fruit and foliage at D.

What I claim therefore and desire to secure by Letters Patent, is
The configuration and ornamentation, The shield, the Urn or Vase,
The strawberry fruit, Vine, and foliage combined, as described, to produce an ornamental design for a handle.

Witnesses.
